[57] CLAIM

The ornamental design for a display adjunct for a telephone base, as shown and described.

DESCRIPTION

FIG. 1 is a top perspective view from the front and the right side of the display adjunct for a telephone base of the invention;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken line showings throughout the views are for illustrative purposes only and form no part of the claimed design. The surfaces obscured by the broken lines are not considered to be a part of the claimed design.
